UNITED STATES PATENT OFFICE

ROBERT PARKER HAYHURST, OF NELSON, ENGLAND

TRACK APPARATUS FOR SPECTACULAR PERFORMANCES

Application filed August 7, 1931, Serial No. 555,846, and in Great Britain August 16, 1930.

This invention relates to apparatus in which spectacular exhibitions by motor-cyclists are adapted to be given to audiences at fair-grounds, music halls or otherwise, of 5 the type known by such designations as "Drome of death", "Wall of death" or otherwise.

Such known apparatus comprises a hollow cylindrical structure with a vertical track of 10 slats or the like having a lower circumferential track or slope to enable the rider to reach a desired speed before he transfers to the vertical track.

With such apparatus, for an adequate exhibition to be afforded, it is necessary for the 15 spectators to mount and stand upon a staging in order to look down into the hollow cylinder, said staging being costly and difficult to transport and erect.

20 The present invention has for its object to provide an apparatus of the type to which the invention relates, but upon which a much more thrilling performance can be given and which moreover will permit the performance 25 to be viewed from the ground, thus enabling if required the staging to be entirely dispensed with.

According to the present invention, a vertical walled track, which may be collapsible, 30 resembling an open-ended cylinder is provided, which may be circular, oval or of other appropriate shape seen in plan. This is preferably made up from a suitable framework and from well spaced slats, so that the wall 35 constituted thereby can readily be seen through.

The vertical walled track thus constituted is mounted in gimbals or on trunnions or 40 shafts in suitably supported bearings to sustain the structure a desired distance from the ground, and hand or power actuated gear is provided to enable the track structure to be rotated around the axis of said gimbals, trunnions or the like.

45 Means are provided to enable a motor-cy-

clist upon a machine to enter and ride around the said vertical walled track when it is in what may be termed the usual horizontal plane, and after the rider and machine have attained the track, it is adapted to be turned 50 around the horizontal axis so that it reaches what may be termed a vertical plane, when the rider and the machine whilst riding round the track also "loop the loop" a desired number of times, before the track is 55 again brought to the horizontal position and the rider and machine are again able to transfer from the vertical walled track to the starting and stopping means.

The preferred means for enabling the rider and machine to be transferred to the vertical walled track may resemble an apparatus such as already known, but adapted to be moved vertically through a desired distance relatively to the vertical walled track mounted 60 in the gimbals or the like. For example, mounted below the revoluble track structure is a shallow basin-like track of closed or open 65 slat construction which is designed normally to occupy a low position, for instance to rest on or near the floor, and means are provided to raise this base-like track upwards to meet or join with the revoluble main track, so that the same can become the base of the latter. The raising and lowering may be effected through suitable apparatus and may 70 be guided as desired.

In order that the invention may be better understood, it will now be described with reference to the accompanying drawings in 80 which:—

Fig. 1 shows somewhat diagrammatically in sectional elevation a preferred apparatus constructed according to the invention.

Fig. 2 shows a side elevation of the apparatus shown in Fig. 1.

Figs. 3, 4 and 5 show diagrammatic elevational views, somewhat in perspective, illustrating the method of using the apparatus according to the invention.

In the drawings, 6 are standards, built up from structural steel members and suitably connected with a base framework 7. At the upper end the standards 6 are provided with 10 bearings 8 for stub shafts or the like 9 connected to a hollow cylindrical framework 10 having the ends open and the curved wall formed from spaced slats such as indicated at 11, it being understood that the slats extend the whole of the way around. The hollow cylindrical structure 10 forms a vertical walled track and may have any required dimensions. In one preferred form, however, the said track may have a diameter of about 15 feet and an axial length of about 8 feet. One of the stub shafts 9 carries a worm wheel 12 with which meshes a worm 13, the shaft of which is carried by suitable bearings and has fixed thereto a sprocket wheel 14 which is connected by a chain 15 with another sprocket 16 carried by a suitable shaft adapted to be actuated from a handle 17. In this manner by turning the handle 17, the vertical walled track 10 can be turned on the stub shafts 9 so that it occupies for example the full line position shown in Fig. 2, or the dotted line position.

Below the vertical walled track 10 is located a shallow basin-like structure comprising a framework carrying a vertical walled track 18 and a lower slope 19 and horizontal platform 20. The vertical walled track 18 and the slope 19 may be formed from slat or similar construction if desired and the whole is carried by lug-like members 21 including travelling nuts 22 carried in guide-ways by the members 23 of the standards 6. Between the members 23 of each of the standards is mounted in bearings a vertical screw 27, so that the said screw can turn but cannot move axially. Each screw engages with a corresponding nut 22 and at its lower end has located thereon a bevel wheel 28 which meshes with a bevel pinion 29 carried by a horizontal shaft 30 supported in bearings by the framework 7. One end of the shaft 30 carries a sprocket wheel 31 connected to another sprocket wheel 32 by a chain 33, the shaft of the sprocket wheel 32 having an actuating handle 34 mounted thereon.

By this means, upon the rotation of the handle 34 the two screws 27 (only one of which is shown in the drawings) are rotated on their axes, and this, causes the nuts 22 to move axially and raise or lower the shallow basin-like structure. If it is in the position shown in Figs. 1 and 2, it may be raised to contact with the lower end of the vertical walled track 10, and when in this position can be lowered to the position shown in Figs. 1 and 2.

For the purposes of utilizing the apparatus, the rider upon a motor cycle enters the basin-like lower structure as indicated in the diagrammatic view, Fig. 3, and this basin-

like structure is then raised until it occupies the position shown in Fig. 4. The rider then starts the machine and runs around the slope 19 thereon, until a desired speed is attained, when the rider transfers to the short vertical track 10. This is the position of the rider shown in Fig. 4.

The lower basin-like track structure is now lowered by the handle 34 and the main vertical walled track is turned by the handle 17 to occupy the dotted position shown in Fig. 2, during the whole of the time the rider on the machine running around the vertical walled track 10. When the vertical position is attained in addition it will be appreciated that the rider is "looping the loop" as indicated in Fig. 5 and that the performance is fully visible to the spectators. Moreover, in addition it will be realized that the performance can also be seen through the spaces between the slats of the tracks.

Whilst the rider is still circling the track 10 it is again turned to the horizontal position, and the lower structure raised to join therewith, permitting the rider to transfer to the lower structure, thence to the slope 19 and to come to rest in the ordinary way.

It is of course obvious that the rider might start up and ride around the lower slope 19 and the lower track 18 when it was in the lower position and while so riding round, be raised before transferring to the track 10.

Although generally speaking a slatted structure is desirable for the tracks, in some cases other open-work structure may be adopted, such for example as a track made from suitably supported expanded metal, perforated metal or otherwise.

Moreover, although it is preferable to utilize the means indicated for enabling the rider and machine to be transferred to and from the vertical walled track, in some cases other means may be adopted. For example, if desired, one open end of the vertical walled track itself may be provided with a sloping portion and a closed centre, and means provided by which the rider and machine can be located at this end, which preferably comes lowermost. For this purpose if desired, the vertical walled track itself may be made to be raised or lowered, or else a ladder or other elevating means may be provided by which the rider and machine can be located in position. With this modification, after the desired speed is attained on the slope portion, the rider will transfer to the vertical wall and then the whole device turned upon the gimbals, stub shafts or the like.

The invention is not limited to the precise forms or details of construction described, as these may be varied to suit particular cases.

What I claim and desire to secure by Letters Patent of the United States of America is:—

1. Exhibition track apparatus for vehicles

comprising a continuous running track, means for so supporting said track that the same can turn on a diametral axis, a starting track, and means for bringing said starting track into engagement with the running track to enable a vehicle to be transferred from one track to the other.

2. Exhibition track apparatus for vehicles comprising a continuous running track, supporting means therefor, means for rotating said running track about a diametral axis, a starting track having a closed bottom and means for raising and lowering said starting track.

3. Exhibition track apparatus for vehicles comprising two upright members, a cylindrical running track open at each end located between said upright members, pivoting means carried by said upright members and

engaging said running track so that the same can rotate about a diametral axis, a bowl-shaped starting track below said running track and means for raising and lowering said starting track relatively to the running track.

4. Exhibition track apparatus for vehicles comprising a continuous running track, means for pivotally supporting said running track whereby it can rotate on a diametral axis and means to convey a running vehicle to said running track.

5. Exhibition track apparatus for vehicles as claimed in claim 4, wherein the running track is formed of a series of spaced slats.

6. Exhibition track apparatus for vehicles comprising two upright supports, a continuous running track pivoted between said supports on a diametral axis, means to rotate said running track about said axis, a starting track slideable on said upright supports and screw means for moving said starting track in a line parallel to said supports into engagement with the running track.

7. Exhibition track apparatus for vehicles comprising two spaced upright supports, an open ended circular track, means for pivoting said running track on a diametral axis, said pivoting means being located at the upper ends of said supports, a dish-shaped starting track having a circular mouth of the same diameter as the running track, and means for bringing said starting track into engagement with one of the open ends of the running track.

8. Exhibition track apparatus for vehicles comprising a circular running track of comparatively small depth relatively to diameter, means for supporting said track so as to rotate about a diametral axis, a starting track below said running track having a closed bottom and an open mouth of the same diameter as the running track and means for raising said starting track into engagement with one end of the running track.

9. Exhibition track apparatus for vehicles as claimed in claim 8, wherein the running track incorporates a peripheral framework and a series of spaced slats fitted transversely to said peripheral framework.

10. Exhibition track apparatus for vehicles comprising two upright members having apertures near their upper ends, a circular running track, pivoted pins projecting from the peripheral face of said running track and engaging in said apertures in the uprights whereby the running track can be rotated on a diametral axis, means for rotating said running track, a starting track below said running track slidably engaging the lower portions of said upright members, and screw means for raising the starting track into engagement with one open mouth of the running track.

11. Exhibition track apparatus for vehicles comprising two upright members having aligned apertures at their upper ends, a running track of circular form of a large diameter relatively to depth, projecting pivot pins on the peripheral wall of said running track at a point midway of the depth thereof and journaled in said apertures in the upright members whereby said running track can rotate on a diametral axis, a worm wheel secured to one of said pivot pins, a worm engaging said worm wheel, manual means for rotating said worm, a dish-like starting track having a closed bottom and an open mouth at the upper end and means for raising said starting track into engagement with one end mouth of the running track.

12. Exhibition track apparatus for vehicles comprising two spaced upright members each composed of two spaced rods, struts for supporting said upright members, a circular running track of comparatively great diameter relatively to depth, radially extending pivot pins on the outer periphery of said running track located midway of its depth and engageable within apertures at the upper ends of said upright members, a starting track having a cylindrical portion of the same diameter as the running track, a coned portion below said cylindrical portion and a closed bottom, means carried on the peripheral wall of said starting track slidably engaging the spaced rods forming the upright members, a threaded spindle associated with each upright member between the two rods composing said upright member, a correspondingly threaded lug on said starting track, means for applying rotation to said screwed spindle to apply movement to said starting track in a vertical direction and means for applying a rotational movement to said running track about the axis through its pivots.

13. Exhibition track apparatus for vehicles comprising a running track, means
